Primary Examiner — Elizabeth J Oswecki

(57) **CLAIM**

The ornamental design for a fastener, as shown and described.

DESCRIPTION

FIG. 1 is a perspective view of a fastener showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view thereof;

FIG. 9 is another perspective view thereof;

FIG. 10 is another perspective view thereof;

FIG. 11 is another perspective view thereof, shown in a used condition;

FIG. 12 is another perspective view thereof, shown in a used condition;

(Continued)

FIG. 13 is another perspective view thereof, shown in a used condition; and,

FIG. 14 is another perspective view thereof, shown in a used condition.

The broken lines in the drawings illustrate portions of the fastener and form no part of the claimed design.

1 Claim, 14 Drawing Sheets
